UNITED STATES PATENT OFFICE.

THOMAS C. BURNS AND FRANK K. HUFFMAN, OF JACKSON, MICHIGAN, ASSIGNORS
TO HAYES WHEEL COMPANY, OF JACKSON, MICHIGAN.

DISK WHEEL.

1,365,452.

Specification of Letters Patent. Patented Jan. 11, 1921.

Application filed June 19, 1920. Serial No. 390,172.

To all whom it may concern:

Be it known that we, THOMAS C. BURNS and FRANK K. HUFFMAN, citizens of the United States, residing at Jackson, Jackson county, Michigan, have invented certain new and useful Improvements in Disk Wheels, of which the following is a specification.

Our invention relates to improvements in disk wheels for vehicles, particularly automobiles.

The object of our invention is to produce a very simple and strong demountable disk wheel for automobiles.

Objects relating to details and economies of construction and operation will definitely appear from the detailed description to follow.

We accomplish the objects of our invention by the devices and means described in the following specification. The invention is clearly defined and pointed out in the claims.

A structure which is a preferred embodiment of our invention is fully illustrated in the accompanying drawing, forming a part of this specification, in which:

The single figure is a radial sectional view from the center of the wheel through the rim.

30 The main disk 1 is flanged into a demountable hub shell 2 at the center. It has a right angle rim flange 3 formed at its periphery to receive a usual or any suitable wheel rim 4. The auxiliary disk 5 is at the back of the wheel and joined at its periphery to the main disk 1 by spot welding at 6. The auxiliary disk 5 is conformed at the center to engage the permanent hub 12 of an automobile and is turned at 7 and flanged outwardly at 8 where it is joined centrally to the main disk 1 by arc welding 9. The auxiliary disk 5 is perforated by a series of holes indicated at 10 to receive the lugs or pins 11, which are disposed on the permanent hub 12.

45 A hub nut 13 is provided for the outer end of the permanent hub 12, and a hub cap 14 embraces the outer end of the hub 2, thus protecting the same against damage.

We have shown the engaging pins engaging the auxiliary disk 5, but the pins might be carried by the disk and engage the permanent hub. We have shown a simple con-

struction of hub nut and cap adapted to this device, but desire to state that others could be adapted thereto in this relation. We desire to claim the invention broadly and also specifically, as pointed out in the appended claims.

Having thus described our invention what we claim as new and desire to secure by Letters Patent is:

1. In a disk wheel construction, the combination of a convexed main disk of sheet metal, with a hub formed integrally therewith, an auxiliary disk convexed and secured to the main disk by spot welding at its periphery and conformed to engage an engaging portion of the permanent hub at the center, with suitable central out-turned flange secured to the main disk by welding, and perforated to engage coupling pins on a permanent hub.

2. In a disk wheel construction, the combination of a convexed main disk of sheet metal, with a hub formed integrally therewith, and flanged at its periphery to receive the rim of an automobile wheel, and an auxiliary disk convexed and secured to the main disk by spot welding at its periphery and conformed to engage an engaging portion of the permanent hub at the center, with suitable central out-turned flange secured to the main disk by arc welding, all coating substantially as described for the purpose specified.

3. In a disk wheel construction, the combination of a convexed main disk of sheet metal, with a hub formed integrally therewith, and an auxiliary disk convexed and secured to the main disk by spot welding at its periphery and conformed to engage an engaging portion of the permanent hub at the center, with suitable central out-turned flange secured to the main disk by welding, as specified.

In witness whereof, we have hereunto set our hands and seals in the presence of two witnesses.

THOS. C. BURNS. [L. S.]
FRANK K. HUFFMAN. [L. S.]
